UNITED STATES PATENT OFFICE.

ALBERT N. WOOD AND FREDERIC M. WOOD, OF BOSTON, MASSACHUSETTS.

DESIGN FOR A HANDLE FOR SPOONS, &c.

SPECIFICATION forming part of Design No. 20,672, dated April 14, 1891.

Application filed March 7, 1891. Serial No. 384,161. Term of patent 3½ years.

To all whom it may concern:

Be it known that we, ALBERT N. WOOD and FREDERIC M. WOOD, of Boston, in the county of Suffolk and State of Massachusetts, have 5 invented a new and useful Design for the Handles of Spoons, &c., of which the following, taken in connection with the accompanying drawing, is a specification.

Our invention consists in a spoon having 10 certain novel features of ornamentation thereon, as shown in the accompanying drawing, which represents a spoon illustrating our design.

The leading features of our design consist 15 in the representation of a windmill in relief upon the face of the handle at or near its broadest end, a harpoon upon the shank of the handle, with its barbed end pointing toward the windmill, and a twisted cord or cable extending from the end of the harpoon 20 opposite its barb, along one edge of the handle around its broad end, and along its opposite side to the same end of the harpoon.

In the drawing, A is the bowl of a spoon, 25 and B is the handle.

C is a representation of an ancient wind-

mill in relief on the smooth field of the central portion of the broader part of the handle.

D is the representation of a harpoon, also in relief, and a a is the representation of a rope 30 or cable extending around the edge of the handle and forming an ornamental finish to the edge of the handle.

What we claim is—

The design for a handle for spoons and 35 similar table-ware herein shown and described, the same comprising the twisted rope-like molding surrounding the edge of the handle, a representation of a windmill upon the broad end of the handle, and a representation of a harpoon upon the shank near the bowl of the spoon, as set forth.

In testimony whereof we have signed our names to this specification, in the presence of two subscribing witnesses, on this 2d day of 40 March, A. D. 1891.

ALBERT N. WOOD.
FREDERIC M. WOOD.
